No. 890,341.

PATENTED JUNE 9, 1908.

J. C. DEAGAN.
MUSICAL BELL.
APPLICATION FILED MAR. 31, 1906.

UNITED STATES PATENT OFFICE.

JOHN C. DEAGAN, OF CHICAGO, ILLINOIS.

MUSICAL BELL.

No. 890,341.

Specification of Letters Patent.

Patented June 9, 1908.

Application filed March 31, 1906. Serial No. 309,151.

To all whom it may concern:

Be it known that I, JOHN C. DEAGAN, a citizen of the United States, residing at Chicago, in the county of Cook and State of Illinois, have invented a certain new and useful Improvement in Musical Bells, of which the following is a full, clear, concise, and exact description, reference being had to the accompanying drawings, forming a part of this specification.

My invention relates to musical bells and particularly to that class of musical bells that are usually sounded by means of hammer blows.

One embodiment of the invention is of particular service as a gong or strike for clocks, organs or pianos, though the use to which the invention is put is not to be thus restricted.

I will explain my invention by reference to the accompanying drawing showing the preferred embodiment thereof, in which—

Figure 1 is a front view of a complete device constructed in accordance with the invention. Fig. 2 is a sectional view on line 2 of Fig. 1. Fig. 3 is a sectional view on line 3 of Fig. 2. Fig. 4 is a front view of the central portion of the tube with the sounding bars removed and showing the throat openings. Fig. 5 is a bottom sectional view on line 5 of Fig. 1. Fig. 6 is a front view showing a detail of the upper portion of the sounding bar or plate. Fig. 7 shows the method of attaching the sound dampers to the hammer stem. Fig. 8 is a sectional view on line 8 of Fig. 6.

Like parts are indicated by similar characters of reference throughout the different figures.

The sounding column or columns are desirably afforded by means of a tubular structure or resonator 9 that may have plugs 10 disposed somewhat near the ends thereof for defining the characteristic of the air columns, though I do not wish to be limited to the plugs 10, nor to their location. Where there is a plurality of sounding plates, I desirably apportion a part of the interior of the tube to each sounding plate. Where there are, as in the embodiment of the invention shown, two sounding plates 11, 12, a portion approximating a half of the interior of the tube (that is a portion approximating half of the space between the plugs 10) is associated with a sounding plate. In the embodiment of the invention shown, the sound-

ing plates are of different lengths, in which event the longer plate desirably has a little more of the interior of the cylinder apportioned to it than is apportioned to the shorter sounding plate.

A zig-zag diaphragm 13 is located at the opening in the tube, the horizontal stretches 13¹ of said diaphragm coöperating with the intervening vertical stretch thereof to completely separate the tube into distinct overlapping air columns, one corresponding to the plate 11 and the other to the plate 12. The general direction of the zig-zag diaphragm is transverse to the length of the tube in which it is contained. Thus, the chamber portion associated with the sounding plate 11 is shaped as most clearly shown in Fig. 3, said figure also showing the shape of the chamber portion associated with the sounding plate 12, these two chamber portions overlapping as indicated in said figure. The throats 14, 15 afforded by said diaphragm lie abreast, the vertically disposed portion of the diaphragm intervening sufficiently between the plates 11, 12 sufficiently to prevent the sound produced from one plate from mingling with the sound apparatus by the other. The diaphragm 13 extends diametrically across the tube, so that the throats 14, 15 have considerable depth.

The intermediate portion of the tube 9 is recessed as indicated most clearly in Fig. 3, so as to accommodate the plates 11, 12 and to permit of a mounting for said plates, said mounting being desirably afforded by means of pins 16 coated with suitable sound-insulating material, which pins project through apertures in the upper ends of the plates 11, 12, the aperture in each plate being afforded with a shoulder or inwardly extending peripheral projection 17 that affords a limited area of engagement between the plate and its support, for the purpose hitherto outlined. The lower ends of the plates are free to swing for the purpose hitherto specified, but, in order that the plates may not be dismounted and may not be permitted excessive swinging or vibratory movement, I provide felt or sound-dampening guards 18, 19, 20, 21, located as shown, the guards 19, 20 being separated a sufficient distance to permit of the desired swinging movement. The sound plates are longitudinally hollowed out or concaved and transversely hollowed out or concaved, as indicated most clearly in Figs. 2 and 5. Where there is a plurality of sound-

ing plates to be sounded simultaneously, the knockers 22 are desirably provided with a single stem 23 carrying a cross-head 24 upon which the knockers 22 are mounted. The 5 stem 23 and the cross-head 24 are desirably formed of wood.

It will be seen from the above that I have provided a musical bell comprising a resonating tube provided with a zig-zag diaphragm 10 in its interior that is extended across the tube between points of the tube displaced longitudinally of the tube, whereby said tube is divided into chambers that extend longitudinally of the tube past each other, said tube 15 having an opening into each chamber, and a sounding plate located before each opening, said openings being located where the chambers of the tube overlap. If the tube 9 is to be suspended, I provide the same with a support 9¹ that carries a lining of sound-dampening material 9² whereby the tube 9 may be supported without permitting the vibrations to be imparted materially to the structure.

The knockers are desirably located to 25 strike the thinnest and most concaved portions of the sounding plates. The stem 23 is pivoted at the upper end of the tube and depends as indicated in Fig. 2. The knockers may be actuated in any suitable way; I have 30 indicated a string 25, adapted to a clock movement. This string may be pulled in opposition to a coil spring 26 and then sufficiently released to permit the knockers 22 to impinge upon the plates 11, 12, by reason of 35 the retractile force of the spring 26. The check spring 27 provided with a contacting block of sound-dampening material 27¹, automatically serves to remove the knockers 22 from engagement with the plates 11, 12 just 40 after said knockers have struck said plates, to permit suitable vibration of said plates. When the knockers are restored to the normal positions indicated in Fig. 2, the sound dampers 29 are brought into contact with the 45 upper edges of the plates to stop their vibration. It should be stated that in the normal position spring 26 is expanded. In the form of the invention shown, there are two such sound-dampers, desirably constructed of wire 50 surrounded with stockinets of rubber or other suitable sound-insulating material.

While in the embodiment of the invention shown, the knockers 22 are given a normal position out of engagement with the plates 55 11, 12, I do not wish to be limited to the precise relative normal positions of the knockers 22 with respect to the plates. It will be noted that the hollows in the sounding plate preferably face outwardly so that the ham- 60 mers directly strike the surfaces thereof.

I claim as new and desire to secure by Letters-Patent the following:

1. A musical bell that includes in its formation a resonating tube provided with a 65 diaphragm in its interior that is extended

across and transverse to the length of the tube between points of the tube displaced longitudinally of the tube, said tube being thereby divided into chambers that extend longitudinally of the tube past each other. 70

2. A musical bell that includes in its formation a resonating tube provided with a zig-zag diaphragm in its interior that is extended across and transverse to the length of the tube between points of the tube displaced 75 longitudinally of the tube, said tube being thereby divided into chambers that extend longitudinally of the tube past each other. 75

3. A musical bell that includes in its formation a resonating tube provided with a 80 diaphragm in its interior that is extended across and transverse to the length of the tube between points of the tube displaced longitudinally of the tube, said tube being thereby divided into chambers that extend 85 longitudinally of the tube past each other, said tube being open, and a sounding plate located before the open portion of the tube.

4. A musical bell that includes in its formation a resonating tube having a zig-zag 90 diaphragm that separates its interior into two overlapping spaces, and sounding plates located before said tube, which tube is provided with openings where said sounding plates are disposed. 95

5. A musical bell that includes in its formation a resonating tube provided with a zig-zag diaphragm in its interior that is extended across and transverse to the length of the tube between points of the tube displaced 100 longitudinally of the tube, said tube being thereby divided into chambers that extend longitudinally of the tube past each other, said tube being open, and a sounding plate located before the open portion of the tube. 105

6. A musical bell that includes in its formation a resonating tube having a zig-zag diaphragm that separates its interior into two overlapping spaces, said tube having 110 openings where the said spaces thereof overlap, and sounding plates located before said openings.

7. A musical bell that includes in its formation a resonating tube provided with a diaphragm in its interior that is extended 115 across and transverse to the length of the tube between points of the tube displaced longitudinally of the tube, whereby said tube is divided into chambers that extend longitudinally of the tube past each other, said tube having an opening into each chamber, and a sounding plate located before each opening. 120

8. A musical bell that includes in its formation a resonating tube having a zig-zag 125 diaphragm that separates its interior into two overlapping spaces, said tube being opened where said spaces overlap, to constitute throats of restricted size as compared with the balance of the spaces. 130

9. A musical bell that includes in its formation a resonating tube provided with a zig-zag diaphragm in its interior that is extended across and transverse to the length of the tube between points of the tube displaced longitudinally of the tube, whereby said tube is divided into chambers that extend longitudinally of the tube past each other, said tube having an opening into each chamber, and a sounding plate located before each opening.

10. A musical bell including an apertured vertically disposed sounding plate, the aperture of said sounding plate being provided with an inwardly extending shoulder, and a pin upon which said shoulder rests, said shoulder affording a limited area of support for the plate upon said pin.

11. A musical bell including a sounding plate concaved longitudinally and transversely.

12. A musical bell that includes in its formation a resonating tube provided with a diaphragm in its interior that is extended across and transversely to the length of the tube between points of the tube displaced

longitudinally of the tube, whereby said tube is divided into chambers that extend longitudinally of the tube past each other, said tube having an opening into each chamber, and a sounding plate located before each opening, said openings being located where the chambers of the tube overlap.

13. A musical bell that includes in its formation a resonating tube provided with a zig-zag diaphragm in its interior that is extended across and transverse to the length of the tube between points of the tube displaced longitudinally of the tube past each other, said tube is divided into chambers that extend longitudinally of the tube past each other, said tube having an opening into each chamber, and a sounding plate located before each opening, said openings being located where the chambers of the tube overlap.

In witness whereof, I hereunto subscribe my name this 19th day of March A. D., 1906.

JOHN C. DEAGAN.
